(57) **CLAIM**

The ornamental design for a switch module, as shown and described.

DESCRIPTION

FIG. 1 is a front isometric view of a switch module embodying our new design;

FIG. 2 is a rear isometric view thereof;

FIG. 3 is a right side elevation view thereof;

FIG. 4 is a front elevation view thereof;

FIG. 5 is a top plan view thereof;

FIG. 6 is a bottom plan view thereof;

FIG. 7 is a rear elevation view thereof;

FIG. 8 is an enlarged front elevation view of the portion thereof circumscribed by arc 8-8 shown in FIG. 4;

FIG. 9 is an enlarged rear elevation view of the portion thereof circumscribed by arc 9-9 shown in FIG. 7;

FIG. 10 is a left side elevation view thereof;

FIG. 11 is an enlarged right side elevation view of the portion thereof circumscribed by arc 11-11 shown in FIG. 3; and,

FIG. 12 is an enlarged left side elevation view of the portion thereof circumscribed by arc 12-12 shown in FIG. 10.

The dash-dash broken line representations in the figures are for the purpose of illustrating unclaimed environment of the claimed design.

1 Claim, 8 Drawing Sheets
